[57] CLAIM

The ornamental design for a wheel lock, as shown and described.

DESCRIPTION

FIG. 1 is a perspective view of the preferred embodiment of my invention taken generally from the front;

FIG. 2 is a perspective view similar to FIG. 1 but taken generally from the rear;

FIG. 3 is a side elevational view with the opposite side being a mirror image thereof;

FIG. 4 is a top plan view with the opposite side being a mirror image thereof;

FIG. 5 is a front elevational view; and,

FIG. 6 is a rear elevational view of the invention.
